WILLIAM SPURWAY.

UNITED STATES PATENT OFFICE.

JOSEPH M. CHRISTIE, OF KIDDERMINSTER, ENGLAND, ASSIGNOR TO LOWELL
MANUFACTURING COMPANY, OF LOWELL, MASSACHUSETTS.

DESIGN FOR CARPET.

Specification forming part of Design No. 7,977, dated January 5, 1875; application filed December 16, 1874.
[Term of Patent 3½ years.]

To all whom it may concern:

Be it known that I, J. M. CHRISTIE, of Kidderminster, England, have invented a new and original Design for Carpets; and I do hereby declare that the following is a full, clear, and exact description thereof, which will enable others skilled in the art to make and use the same, reference being had to the accompanying photographic illustration, forming part of the specification.

I claim as my invention—

The design for carpets, as shown.

J. M. CHRISTIE.

Witnesses:

JAMES ARCH,

WILLIAM SPURWAY.
